(57) **CLAIM**

We claim the ornamental design for a control device, as
shown and described.

DESCRIPTION

*This application is a continuation reissue of prior pending
U.S. application Ser. No. 29/695,315, which is an applica-
tion for reissue of U.S. Pat. No. D. 807,763, which issued
from prior U.S. application Ser. No. 29/578,733, filed Sep.
23, 2016, which is a continuation of prior U.S. application
Ser. No. 29/515,922, filed Jan. 28, 2015, now U.S. Pat. No.
D. 769,829, issued Oct. 25, 2016; the entireties of which are
expressly incorporated by reference herein.*

FIG. 1 is a perspective view of a control device showing our
new design.

FIG. 2 is a front view thereof.

FIG. 3 is a left side view thereof.

FIG. 4 is a right side view thereof.

FIG. 5 is a top view thereof; and,

FIG. 6 is a bottom view thereof.

The rear [views] view forms no part of the design and is
omitted. The portions of the drawings appearing in broken
lines are for environment only and do not form part of the
claimed design.

1 Claim, 8 Drawing Sheets

**Matter enclosed in heavy brackets [ ] appears in the
original patent but forms no part of this reissue; matter
printed in italics indicates the additions made by reissue.**

CANCELLED

Related U.S. Application Data

application for the reissue of Pat. No. Des. 807,763, which is a continuation of application No. 29/515, 922, filed on Jan. 28, 2015, now Pat. No. Des. 769,829.
